UNITED STATES PATENT OFFICE.

JOHN WEST, OF BROOKLYN, NEW YORK, ASSIGNOR TO THE MANHATTAN TYPE FOUNDRY, OF NEW YORK.

DESIGN FOR A FONT OF PRINTING-TYPE.

SPECIFICATION forming part of Design No. 17,353, dated May 17, 1887.

Application filed March 15, 1887. Serial No. 231,049. Term of patent 7 years.

To all whom it may concern:

Be it known that I, JOHN WEST, a citizen of the United States, and residing at the city of Brooklyn, county of Kings, and State of New York, have invented a certain new and original Design for a Font of Printing-Type; and I do declare the following to be a full, clear, and exact description of the invention, reference being had to the accompanying fac-simile typographic impression, which forms part of this specification.

My design consists of a font of printing-type comprising heavy lines at the top and bottom of the letters and light interior and vertical lines, and having portions of the letters extending above and below the line of print. These features, I am aware, are not new, and I lay no claim to originality in that regard; but I have combined with these features others which possess novel and, as I believe, attractive features.

The letters A B C E F G H K L M O Q R S V W X Y &, the figures 0, 4, and 8, and the lower-case letters a f g h k m n o t u v w x y have portions of their lines gradually thickening from a hair-line to a wider line, and at the termination of the widest portion of the line a small ornamental hair-line curve is added, which has a direction at an acute angle to the line to which it is added, and which terminates in a dot.

The letters A D I J N T U Z, the numerals 1 2 3 5 6 7 9, and the lower-case letters c d j p z, and the mark † all have the feature of the hair-line curve and dot; but it is attached to a heavy horizontal line in these cases, and not to one gradually thickened. 35

The letters A B E F P R and the lower-case letters b, e, i, l, q, and s have portions of their lines gradually thickening from hair-lines to ones of greater width, forming cusps. The punctuation-marks are not peculiar, except the mark ? above mentioned.

Having described my invention, what I claim as new is— 45

The design for a font of printing-type, as shown and described, consisting of letters having heavy lines at the top and bottom, with light interior lines extending (some of them) above and below the normal line of print, having some lines gradually increasing in width from hair-lines to wider lines, and having in some letters, and making acute angles with the said wider lines, terminations of hair-line curves ending in a dot. 50

In testimony whereof I affix my signature in presence of two witnesses. 55

JOHN WEST.
